N. V. DYER.
SKIVING MACHINE.
FILED SEPT. 19, 1919.

INVENTOR
Neville V. Dyer
By his Attorney,
Nelson M. Howard

UNITED STATES PATENT OFFICE.

NEWELL V. DYER, OF HOLBROOK, MASSACHUSETTS, ASSIGNOR TO UNITED SHOE MACHINERY CORPORATION, OF PATERSON, NEW JERSEY, A CORPORATION OF NEW JERSEY.

SKIVING MACHINE.

Application filed September 19, 1919. Serial No. 324,891.

To all whom it may concern:

Be it known that I, NEWELL V. DYER, a citizen of the United States, residing at Holbrook, in the county of Norfolk and State 5 of Massachusetts, have invented certain Improvements in Skiving Machines, of which the following description in connection with the accompanying drawings, is a specification, like reference characters on the 10 drawings indicating like parts in the several figures.

This invention relates to skiving machines and is herein illustrated as embodied in a skiving machine of the Amazeen type such 15 as is shown in the patent to Alexander, No. 1,180,222.

In that patent there is shown among other features a skiving knife, a feed roll, a presser foot the operative face of which is normally 20 substantially parallel to the adjacent element of the roll, and means for supporting both ends of the foot yieldingly so that a substantially uniform pressure is applied to the work throughout the portion engaged 25 by the foot. This presser foot has proved very successful and has gone into wide use. Its construction, however, is somewhat complicated; and, after the parts have become 30 worn, the foot tends to be turned by the work about an axis substantially parallel to the axis of the roll and thereby, by coming into contact with the edge of the knife, to dull said edge.

The general object of the present invention 35 is to provide in a skiving machine a presser foot of simple construction which possesses the advantages and is free from the disadvantages of the patented construction. In order to simplify the construction 40 the outer end of the illustrative foot is supported at the end of a leaf spring thereby doing away with certain pivots and levers; and, in order to prevent the foot from being 45 turned or oscillated so as to come into contact with the edge of the knife, inter-engaging guiding means are provided on the foot and on a stationary part of the machine.

These and other features of the invention 50 including certain details of construction and combinations of parts will be described as

embodied in an illustrative machine and pointed out in the appended claims.

Referring now to the accompanying drawings,—

Fig. 1 is a front elevation of a portion of 55 a skiving machine in which the present invention is embodied, and

Fig. 2 is a view on an enlarged scale principally in elevation, showing more in 60 detail the construction of the presser foot.

In the drawings the invention is shown as embodied in the well-known Amazeen skiving machine. In this machine the work is fed against the edge of a rotary disk knife 3 65 by a rotary feed roll 5 and a rotary feed disk 7, the roll having a cylindrical surface which co-operates with the feed disk and a frusto-conical surface which supports that portion of the work which is being skived. 70 The angle of the scarf produced is determined by the relative position of the frusto-conical portion of the feed roll and the knife; and it is important that the work be pressed firmly and uniformly against 75 the periphery of this portion of the feed roll.

In the construction shown the margin of the work acted upon by the knife is pressed 80 against the periphery of the feed roll directly in advance of the knife edge by a presser comprising a foot 9 the outer end of which is fastened by rivets 11 to the reversely bent end of a leaf spring 13, the foot having formed integral therewith guide 85 flanges 14 which contact with the edges of the leaf spring. A headed pin 15 extends through a perforation in the leaf spring and is driven into the foot 9; and a coiled spring 17, which surrounds the stem of the pin, 90 normally holds the head of the pin down against the leaf spring with the presser foot in the position shown in Fig. 1.

The inner end of the leaf spring is fastened by a screw 19 to an edge gage block 95 21 provided with a finger 23, the under surface of the block and finger being shaped to fit the periphery of the roll. In order to supplement the pressure exerted by the leaf spring, if desired, a knurled thumb nut 100 25 is provided which is threaded on a pin 27. This pin extends through a slot in the

leaf spring and is threaded into the block 21, a coiled spring 29 being interposed between the thumb nut and the leaf spring. By screwing the nut 25 down or up the 5 downward pressure of the foot 9 upon the work 100 may be varied. In order to permit adjustment of the foot, a screw 31 having a knurled head 33 is threaded through the leaf spring and bears with its lower end 10 upon the block 21, a check nut 35 being provided to hold the screw in adjusted position.

The mounting of the block 21 is or may be substantially the same as in the patented 15 machine, the lower end of the arm 121, by which the block is carried, being adjustable along a guide rib 37 which in turn is angularly adjustable on a plate 39, the plate being hinged to a base plate 41 so that the 20 block 21 and all of the parts which are associated with it may be swung down out of the way when access to the knife is desired. A knurled clamping nut 43 threaded upon a pin 45, which is pivoted at its base to a 25 stationary part of the machine, holds the plate 39 in the position shown. By unscrewing the nut and swinging the pin upwardly, the plate may be freed to be swung downwardly.

30 When the work enters between the presser foot and the feed roll, the leaf spring will yield as a whole to permit the foot to rise. At the same time the reversely curved portion of the leaf spring will bend to permit the outer end of the foot to rise, and the spring 17 will yield to permit the inner end of the foot to rise. As a result, the foot will move substantially vertically in 35 parallel relation to the roll if the thickness 40 of the work is uniform but will tilt somewhat if the work is beveled as will be the case where reskiving is being done.

In order to prevent the foot from being turned about an axis transverse to the 45 direction of feed of the work, which might result in causing the foot to contact with the knife, interengaging guiding means are provided between the foot and the block 21, the outer end face of which serves as 50 an edge gage. In the operative face of the block is cut a vertical groove 47 into which projects a pin 49, the pin being driven into the foot 9 so that the pressure exerted by the work in the direction of the feed is 55 prevented from tilting the foot about an axis transverse to the direction of feed.

Although the invention has been set forth as embodied in a particular construction and in connection with a skiving machine 60 of the Amazeen type, it should be understood that the invention is not limited in the scope of its application to the particular construction nor to the particular type of machine which has been shown and described.

Having thus described my invention, what I claim as new and desire to secure by Letters Patent of the United States is:

1. A skiving machine, having in combination, a knife, a feed roll, an edge gage 70 block, a leaf spring fastened to the block in such manner that its outer end is movable toward and from the roll, a presser foot fastened rigidly to the outer end of the leaf spring, and a spring located between the inner end of the foot and the leaf spring. 75

2. A skiving machine, having in combination, a knife, a feed roll, a presser foot having its work engaging face normally parallel to the adjacent portion of the work 80 engaging face of the roll, a yielding support for the outer end of the foot, means for supporting the inner end to yield independently, and interengaging guiding means formed on the foot and on a stationary part of the machine for guiding the foot in its yielding movement. 85

3. A skiving machine, having in combination, a knife, a feed roll, a presser foot having its work engaging face normally 90 parallel to the adjacent portion of the work engaging face of the roll, a yielding support for the outer end of the foot, means for supporting the inner end to yield independently, and means including a pin and 95 slot connection between the foot and a rigid part of the machine for guiding the foot in its yielding movements.

4. A skiving machine, having in combination, a knife, a feed roll, a stationary 100 member, a leaf spring mounted on the stationary member in such manner that its outer end is yieldable toward and from the roll, a presser foot carried by the outer end of the leaf spring, means for yieldingly 105 opposing movement of the inner end of the foot away from the roll, and co-operating guiding means on the presser and stationary member constructed and arranged to prevent tilting of the presser about an axis 110 parallel to the axis of rotation of the roll.

5. A skiving machine, having in combination, a knife, a feed roll, a stationary member, a leaf spring mounted on the stationary member in such manner that its 115 outer end is yieldable toward and from the roll, a presser foot carried by the outer end of the leaf spring, means for yieldingly opposing movement of the inner end of the foot away from the roll, and co-operating guiding means on the presser and stationary member constructed and arranged to compel movement of the presser toward and from the roll to take place in a straight path. 120

6. A skiving machine, having in combination, a knife, a work support, a yielding presser foot arranged to co-operate with the work support and interengaging guiding means formed on the foot and on a 130

stationary part of the machine for maintaining the foot upright during its yielding movements toward and from the work support.

5 7. A skiving machine, having in combination, a knife, a feed roll, a yielding presser foot arranged to co-operate with the feed roll, and interengaging guiding means formed on the foot and on a stationary 10 part of the machine for maintaining the foot upright during its yielding movements toward and from the roll.

15 8. A skiving machine, having in combination, a feed roll, an edge gage block, a leaf spring fastened at its inner portion to

the block and having a reversely curved outer end, and a presser foot carried by the reversely curved portion.

9. A presser foot construction comprising a leaf spring adapted to be fastened to a stationary part of a machine in such manner that one end is free to yield, the free end having a reversely curved portion, a presser foot fastened to the reversely curved portion, and a spring located between one 20 25 end of the presser foot and the leaf spring.

In testimony whereof, I have signed my name to this specification.

NEWELL V. DYER.
